UNITED STATES PATENT OFFICE.

ATTILIO ZANCHI, OF SAN PIETRO-SEVESO, ITALY.

LOOM.

1,319,827.

Specification of Letters Patent. Patented Oct. 28, 1919.

Application filed March 31, 1916. Serial No. 88,158.

To all whom it may concern:

Be it known that I, ATTILIO ZANCHI, a citizen of Italy, residing at San Pietro-Seveso, Italy, have invented certain new and 5 useful Improvements Relating to Looms, of which the following is a specification.

This invention relates to looms for making fabrics of silk, cotton and similar fine materials of the kind already known, where- 10 in the beam is stationary and carries a closed reed which is adapted to be reciprocated thereon, while in addition an open oscillatory reed is provided adapted to beat up the weft, this oscillatory reed receiving an 15 accelerated movement when engaging with the shed. The object of the invention however is that the teeth of the open reed are yieldingly connected together near their free ends and are rounded off backwardly 20 from the point at which they first engage with the shed. Near to the point where the open reed first enters the shed, is arranged a bar which extends across the whole width 25 of the shed, and has a limited oscillatory movement, adapted shortly before the reed enters the shed, to raise the shed slightly and to spread the warps out flat so as to insure a correct and uniform engagement thereof by the reed.

30 In the accompanying drawing is illustrated a constructional example of the invention, the drawing being partly diagrammatic.

Figure 1 is a vertical section, partly in 35 elevation of a portion of a loom.

Figs. 2 and 3 show details to a larger scale.

Fig. 4 shows also to a larger scale, an elevation of the device for reciprocating the 40 closed reed.

In the loom illustrated the closed reed 2 (guide reed) mounted upon the stationary beam 1 is adapted to be reciprocated longitudinally within determined limits by 45 means of mechanism hereinafter described. The open reed (beating reed), provided with two rows of teeth 3, 3' is keyed upon a shaft 4 carried at its ends in supports 5, these latter being adapted to swing within

50 determined limits upon a shaft 6. The swinging movement is imparted to the supports 5 by two pitmen 7 (only one being shown in the drawings) operated from the crank shaft 8. The latter also drives the 55 shaft 9 on which is keyed a bevel wheel 10 gearing with a bevel wheel 11. The latter

is mounted upon a shaft 12, carried in supports 13 and 14, and having keyed upon its other end a bevel wheel 15 gearing with a bevel wheel 16 keyed on the shaft 6 and 60 gearing with a bevel wheel 17. The latter is mounted at the lower end of a shaft 18 disposed at the side of one of the supports 5 and carrying at its upper end a worm wheel 19 gearing with a worm 20 mounted 65 upon the shaft 4 so as to effect the turning of the open reed 3, 3'. The ratio of reduction between the driving crank shaft and the open reed is such that during each revolution of the crank shaft 8 the open reed 70 makes a half revolution so that the reed teeth 3 and 3' alternately operate to beat up successive wefts. Each row of teeth 3 and 3' passes through the coils of two spiral springs 21 and 22 (Figs. 2 and 3) ex- 75 tending across the whole length of the teeth rows by means of which they are held at uniform distances apart. The teeth are held in the reed base and soldered or otherwise secured to the springs 21, while they are 80 held yieldingly in the springs 22 so that if a thick place occurs in the shed 24, 25, the teeth engaging with this can spread out with the spring coils as shown in Fig. 3. At the front and back faces of the teeth- 85 rows, half round rods 26 are inserted into the spiral springs in order to hold the teeth in correct alinement. The free ends of the teeth are backwardly rounded off (Fig. 2) from the point at which they enter the shed 90 so as to insure an easy passage of the teeth into the shed and when the teeth pass out of the shed the latter is rapidly released from the teeth.

Under the shed 24, 25 and extending over 95 the whole width thereof there is mounted in front of the beam 1 a bar 27 which makes a partial turning movement to and fro. This bar is connected to one end of a link 28 (Fig. 1). The other end of the link is 100 connected to a member 30 pivoted at 29 to the loom frame. The member 30 is connected by a pitman 31 to an arm 33 pivoted at 32, and carrying a roller 34 running on a cam 35 keyed to the shaft 6. 105

The device for reciprocating the reed 2 (Fig. 4) comprises a bracket 36 rigidly secured to the beam 1, on which bracket is mounted a ratchet wheel 37 and a star wheel 38 rigidly secured to the ratchet wheel. The 110 ratchet wheel has also fixed thereon an eccentric 39 engaging with an eye in an arm

40 secured to the reed 2. A ratchet lever 41 with a pawl 42 is connected to a rod 43 which is periodically raised by an open-double eccentric (heart cam), mounted upon 5 the lower shaft (not shown) of the loom, in such a manner that at each throw of the weft a rotary movement is imparted to the ratchet wheel. This movement can be so adjusted that the ratchet wheel is moved 10 one, two or three tooth spaces turning the eccentric 39 on which the movement of the reed 2 depends; this mechanism can of course be put out of operation when required.

15 The lever 44 acts as a pawl checking the turning of the star wheel 38 and the ratchet wheel 37 periodically.

When the loom described is in operation the pitmen 7 and thus also the supports 5 20 are oscillated by the crank shaft and at the same time the open reed 3, 3' is rotated by means of the members 10, 11, 12, 15, 16, 17, 19, 20 in order to beat up the wefts in the fabric. When a row of teeth is approaching 25 the shed 24, 25, the supports 5 are swung toward the left, that is to say in a direction opposed to the turning of the bevel wheel 16 so that the bevel wheel 17 will be turned more rapidly thereon and 30 thus impart an accelerated turning movement to the reed 3, 3'. In this manner the weft is effectively beaten into the fabric. The row of teeth approaching the shed only enters the latter a short distance behind the 35 weft to be beaten up; in this manner the shed fibers are saved from needless wear. In consequence of the flexibility of the free ends of the reed teeth they can easily pass over any irregularities (knots and so forth) 40 in the shed fibers, so that breakages due to this cause are avoided. As two rows of teeth are provided on the open reed the so-called "slay separation" in the fabric is considerably reduced; in order to increase this 45 effect the rows of teeth are preferably so arranged that the teeth of one row are between the teeth of the other row. The reciprocating movement of the closed reed 2 also assists in attaining this end as the 50 warps are always so displaced that the teeth of the open reed will come successively between different groups of warps. Shortly before a row of teeth enters the shed, the arm 33 is raised by the cam 35 and the bar 55 27 is turned into the position shown in Fig. 2, by the link mechanism 31, 30, 28, in which position it raises the shed thus spreading the warps, and distributing them uniformly throughout the width of the shed. In this 60 manner the correct and uniform entry of the rows of teeth 3, 3' into the shed is insured while at the same time any "slay separation" is avoided. In consequence of the uniform distribution of the shed easy separa-

tion thereof is attained on the rapid upward movement of the warps. The opening in the shed may in this case be smaller than usual as the shuttle moves on a stationary beam; the warps are therefore stretched to a less extent and are not subjected to as 70 much tension.

The loom described possesses the advantage that the number of divisions of the closed reed as well as the number of teeth of the open reed can be considerably reduced, thus naturally also reducing the friction on the shed; this permits of more easy and rapid working of the loom and consequently greater efficiency with less consumption of power. This is also due to the fact 75 that the beam with the closed reed is no longer reciprocated which is a considerable saving in power. The fabric produced on such a loom is so to speak, faultless and so compact that a subsequent tightening by 80 means of a special tightening machine is unnecessary.

Being aware that it is not new to use open reeds on intermittently rotating shafts with an accelerated movement for beating up the 90 weft and that it is not new to give a side-wise movement for the closed reed or to the shed in order to avoid "shed separation" and to employ reeds with wire coils as spacing means, I do not claim such devices 95 such devices being not sufficiently adapted for working fine fabrics in a perfect manner, but what I claim as new and desire to secure by Letters Patent is:—

1. In a loom for making fabrics of silk, 100 cotton and other fine materials, the combination of a rotary shaft, means for supporting the same, for turning it, and for imparting a lateral reciprocating movement thereto, a member fixed on said shaft, a row 105 of teeth supported in the said member with means for spacing them apart, a bar extending across the loom adjacent to and behind the point at which the said teeth engage with the warp threads which form the shed, and means for turning the said bar at intervals in order to raise the warp threads which form the shed and to spread out the threads thereof before the teeth of the rotary member engage with the said threads. 110

2. In a loom for making fabrics of silk, 115 cotton and other fine materials, the combination of a rotary shaft, means for supporting the same, for turning it, and for imparting a lateral reciprocating movement 120 thereto, a member fixed on said shaft, a plurality of rows of teeth carried in said member, flexible means for spacing apart the teeth of the said rows, means for lifting at intervals the warp threads which form the shed behind the point at which the teeth of the beating up member engage therewith, and means for driving the shaft at such a 125

speed that the sets of teeth will come successively to the operative position for beating up the successive wefts.

3. In a loom for making fabrics of silk, cotton and other fine materials, the combination of a revoluble toothed member for beating up the weft, and mechanism for oscillating and for turning said toothed member, a stationary beam, a reed frame 10 adapted to slide laterally in said stationary

beam, and means for imparting at intervals movements first in one direction and then in the other to said laterally movable reed.

In testimony whereof I affix my signature in presence of two witnesses.

ATTILIO ZANCHI.
